BEVERAGE DISPENSER

Julian D. Gordon, Peabody, Mass., assignor to Jet Spray
Cooler, Inc., Waltham, Mass., a corporation of Massachusetts

Filed Nov. 9, 1964, Ser. No. 82,563

Term of patent 14 years

(Cl. D2—3)

FIG. 1

FIG. 2

FIG. 3

FIG. 4

FIG. 5

FIG. 6

FIG. 7

FIG. 1 is a perspective view of a beverage dispenser showing my new design;

FIG. 2 is a front view thereof;

FIG. 3 is a side view thereof;

FIG. 4 is a rear view thereof;

FIG. 5 is a front view of a second embodiment of a beverage dispenser showing my new design;

FIG. 6 is a front view of a third embodiment of a beverage dispenser showing my new design; and

FIG. 7 is a side view of a fourth embodiment of a beverage dispenser showing my new design.

In the embodiment of beverage dispenser shown in FIGS. 1-4, the side not shown is the same as the side shown.

In the embodiment shown in FIG. 5, the sides and rear are the same as those in the embodiment of FIGS. 1-4.

In the embodiment of FIG. 6, the sides and rear are the same as in the embodiment of FIGS. 1-4 except that the bowl does not have the step at the bottom.

In the embodiment of FIG. 7, the front and rear are the same as in the embodiment of FIGS. 1-4, and the side not shown is the same as the side shown.

I claim:

The ornamental design for a beverage dispenser, as shown and described.
